UNITED STATES PATENT OFFICE.

RONALD A. McCANN, OF SWISSVALE, AND LLOYD V. LEWIS, OF EDGEWOOD BOROUGH, PENNSYLVANIA, ASSIGNORS TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 17, 1922. Serial No. 595,068.

To all whom it may concern:

Be it known that we, RONALD A. McCANN and LLOYD V. LEWIS, citizens of the United States, residing at Swissvale and Edgewood Borough, respectively, in the county of Allegheny and State of Pennsylvania, have invented certain new and useful Improvements in Railway-Traffic-Controlling Apparatus, of which the following is a specification.

Our invention relates to railway traffic controlling apparatus, and particularly to apparatus of the type in which cars or trains are governed by energy received from the track rails.

We will describe two forms of apparatus embodying our invention, and will then point out the novel features thereof in claims.

In the accompanying drawings, Figs. 1^A and 1^B are diagrammatic views, which, when placed end to end in the order named, illustrate one form of apparatus embodying our invention. Fig. 2 is a view similar to a portion of 1^B but illustrating a modification of our invention.

Similar reference characters refer to similar parts in each of the views.

Referring first to Figs. 1^A and 1^B, the reference characters 2 and 2^a designate the track rails of a single track over which traffic moves in both directions, the stretch of track shown in the drawing including a passing siding G. The track rails are divided by insulated rail joints 3 into a plurality of successive track sections 4—5, 5—6, 6—7, etc.

Traffic along the portion of track shown in the drawing from left to right is governed by a plurality of roadside signals S', S³, S⁵ and S⁷, while traffic along this same stretch from right to left is governed by a plurality of similar signals S², S⁴, S⁶ and S⁸. As here shown, each signal is located adjacent the junction of two track sections although this exact location is not essential. Each signal in the form illustrated in the drawings is of the three-position semaphore type arranged to indicate "stop", "caution" and "proceed".

Track section 5—6 is provided with a track circuit comprising means for supplying alternating current to the track rails adjacent the middle of the section and two

track relays T³ and T⁴ normally connected with the track rails adjacent the two ends of the section respectively. In the arrangement shown in Fig. 1 a transformer 86 constitutes the immediate supply of alternating current to the track rails at the middle of this section, the secondary of this transformer being directly connected across the rails of the section. The primary of transformer 86 is provided with two sources of current, one of which is a transformer 87, the secondary of which is connected with the primary of transformer 86 through front contacts of a third track relay B', which track relay is connected across the rails of section 5—6 adjacent the middle of the section, an impedance being included between this relay and one of the track rails. The primary of transformer 87 is connected with a transmission line L to which alternating current is constantly supplied by a generator 8. The other means for supplying current to the primary of transformer 86 will be explained hereinafter.

Track section 6—7 is provided with a track circuit which is similar in all respects to the track circuit for section 5—6, and the same thing is true of the partial track section shown to the right of point 7.

The track section 4—5, which includes the siding G, is provided with a special track circuit comprising a track relay T⁶ normally connected across the rails adjacent the right-hand end of the section, a track relay T' constantly connected across the rails adjacent the left-hand end of the section, and a transformer C' normally connected across the rails at the same point as track relay T'.

We have stated that certain of the track relays are normally connected with the rails of the several track sections. As will appear hereinafter, these track relays are at times disconnected from the rails and sources of alternating current are connected to the rails in their places for reasons which will also appear as the explanation of the apparatus proceeds.

Each signal S is controlled by a line relay which is designated by the reference character A with the same exponent as that applied to the associated signal.

Each signal is provided with a caution controlling circuit and a proceed controlling circuit. Referring particularly to signal

S^s , the caution circuit is from the secondary of transformer U^s , through wires 9 and 10, left-hand point of contact 11 of relay A^s , wire 12, operating mechanism of signal S^s , 5 wire 13, left-hand point of contact 14 of relay A^s , and wires 15 and 16 to the secondary of transformer U^s . This circuit is closed only when relay A^s is energized by current of such polarity that its contact fingers are 10 swung to the left, which current we will term current of "reverse relative polarity." It should here be stated that each relay A is of such type as to respond to reversals of the relative polarity of the alternating current supplied to the winding thereof shown in the drawing, and this is accomplished by providing the relay with a second winding which is constantly supplied with alternating current in accordance with the usual 15 practice. The second winding is omitted from the drawings to simplify the disclosure. The proceed indication circuit for signal S^s is from the secondary of transformer U^s , through wires 9 and 10, the right-hand point 20 of contact 11, wire 17, operating mechanism of signal S^s , wire 13, right point of contact 14, and wires 15 and 16 to the secondary of transformer U^s . It will be seen that this proceed circuit is closed only when 25 relay A^s is energized by current of such polarity that the contact fingers of this relay are swung to the right, which current we will term "current of normal relative polarity." The primary of transformer U^s is supplied 30 with alternating current from the transmission line L .

The control of each signal S by its associated line relay A is the same as the control of signal S^s by relay A^s .

40 Line relay A^s is provided with a controlling circuit which is as follows: from the secondary of transformer U^s , through wire 18, pole-changer P^s operated by signal S^s , wires 19 and 20, contact 21 of line relay A^s , wires 22 and 23, contact 24 of track 45 relay T^s , wire 25, contact 26 of track relay T^s , wire 27, winding of relay A^s , wires 28 and 29, pole-changer P^s , and wire 30 to the secondary of transformer U^s . It will be noted that this circuit is controlled by 50 both track relays T^s and T^s for track section 5-6, so that the circuit will be open when any part of this section is occupied by a train. The circuit is also controlled by line relay A^s so that the circuit is likewise open whenever the latter line relay is de-energized. The circuit furthermore includes pole-changer P^s which is operated by signal S^s in such manner that when the latter signal indicates "proceed" or "caution" the current supplied to relay A^s is of normal relative polarity but that when signal S^s indicates stop the current supplied to relay A^s is of reverse relative polarity.

55 The circuit for relay A^s is provided with

a branch around contact 21 of line relay A^s , which branch passes from wire 19, through wires 34 and 33, contact 32 of an auxiliary relay X^s and wire 31 to wire 23. It follows that when relay X^s is energized, line relay A^s is eliminated from the control of the circuit for line relay A^s .

The auxiliary relay X^s is provided with a pick-up circuit which passes from secondary of transformer U^s , through wires 18 and 35, back contact 36 of track relay T^s , wires 37 and 38, contact 59 operated by signal S^s , wire 39, winding of relay X^s , and wires 40 and 30 to the secondary of transformer U^s . Contact 59 is closed only when signal S^s indicates proceed or caution, and so relay X^s can be picked up only when a train moving toward the right enters section 6-7 and then only if signal S^s is in one of the positions specified. As soon as signal S^s moves beyond the caution position in response to the entrance of such train into the section, the pick-up circuit for relay X^s is open, but in the meantime a stick or holding circuit has been closed, which circuit is from the secondary of transformer U^s , through wires 18 and 35, back contact 36 of track relay T^s , wire 41, contact 42 of relay X^s , wire 43, winding of relay X^s , and wires 40 and 30 to the secondary of transformer U^s . For reasons which will be explained hereinafter, track relay T^s remains open until the rear of the train passes out of section 6-7 and so it will be seen that relay X^s remains closed as long as section 6-7 is occupied by any portion of the train.

The control of each line relay A^s , A^7 , A^2 , and A^8 is the same as the control of line relay A^s .

When signal S^s indicates "proceed" or "caution" the line relay A^s is provided with a "normal" circuit which passes from the secondary of transformer U^s , through wire 44, contact 45 closed when signal S^s indicates "proceed" or "caution", wires 46 and 47, contact 48 of track relay T^s , wires 49 and 50, contact 51 of track relay T^s , wire 52, contact 53 of track relay T^s , wire 54, winding of relay A^s , wires 55, 56 and 57 to the secondary of transformer U^s . When signal S^s indicates "stop" the circuit for line relay A^s includes the secondary of the reversing transformer H^s , whose primary is supplied constantly with energy from transformer U^s over wires 44 and 57. This latter circuit is termed the "reverse" circuit of A^s , and passes from the secondary of H^s , through the contact of circuit controller 45 closed when signal S^s indicates "stop", wires 46 and 47, contact 48, wires 49 and 50, contact 51, wire 52, contact 53, wire 54, winding of relay A^s , wires 55, 56 and 57, to the secondary of transformer H^s . In so far as the circuits just traced are concerned, the signal S^s will indicate "stop" whenever

any one of the track relays T^8 , T' and T^6 are open, will indicate "caution" when these relays are closed and signal S^8 indicates "stop", and will indicate "proceed" when these relays are closed and signal S^8 indicates "caution" or "proceed". These circuits are provided with a branch around contact 48 of relay T^8 , however, which branch passes from wire 46, through wire 46^a, contact 81 of auxiliary relay X^8 , and wire 82 to wire 50. The control of relay X^8 is similar to the control of relay X^5 , and inasmuch as relay X^8 is closed when a train moving toward the left passes signal S^8 , it will be seen that at such time signal S^8 will move to the "caution" position as soon as the rear of the train passes S^8 , and to the "proceed" position as soon as signal S^8 moves to the caution position; while if T^8 is open due to a train approaching S^8 from the left, both S^8 and S^6 will indicate "stop".

The control of line relay A' is similar to the control of line relay A^6 , and, consequently, further explanation will not be necessary.

The circuit for line relay A^4 is from the secondary of transformer U^5 , through wire 60, contact 61 of a relay W^6 , wires 62 and 63, contact 64 of track relay T^8 , wire 65, contact 66 of track relay T^4 , wire 67, winding of relay A^4 , wires 68, 29 and 70, contact 71 of relay W^6 , and wire 55 to the secondary of transformer U^5 . The contacts 61 and 71 of relay W^6 , which are included in this circuit, constitute a pole-changer by virtue of which current of normal or reverse relative polarity is supplied to relay A^4 according as relay W^6 is closed or open.

Relay W^6 is normally closed by virtue of a circuit which passes from the secondary of transformer U^4 , through wires 44 and 72, contact 73 of line relay A^8 , wires 74, 75, 76 and 77, contact 78 operated by signal S^8 , wire 79, winding of relay W^6 , and wires 80, 55, 56, and 57 to the secondary of transformer U^4 . This circuit is provided with two branches around contact 73 of relay A^8 . One branch passes from wire 44, through wire 160, contact 161 operated by signal S^8 , wires 162 and 75 to wire 76. The other branch passes from wire 44 through wire 90, contact 89 of relay X^8 , and wire 91 to wire 76. It will be seen, therefore, that relay W^6 is de-energized as soon as relay A^8 is opened by a train moving toward the right, but that when a train passes signal S^8 moving toward the left, relay W^6 will become closed at once. The result of this control is that when signal S^8 is placed at stop by a train moving toward the right, signal S^8 is at caution and signal S^6 is at caution or stop, but that when a train moves toward the left, signal S^8 returns to the proceed position and signal S^6 to the caution position as soon as the train passes signal S^8 .

The control of relay W' associated with signal S' is the same as the control of relay W^6 , although the signal which is controlled by relay W' is not shown in the drawings.

The apparatus shown in the present application is intended for co-operation with suitable train-carried governing mechanism for the control of the speed of the train. This train-carried governing mechanism is controlled in part by the track circuit current through the medium of receiving appliances at the front end of the train, and so it is obvious that a source of track circuit current must always be connected across the track rails ahead of the train. In so far as the apparatus thus far referred to is concerned, it will be seen that when a train moving toward the right enters section 5-6 it will receive alternating track circuit current until the point is reached at which relay B' opens; beyond this point, a source of current is provided in advance of the train, however, by the apparatus which we will now explain.

Referring particularly to track section 5-6, relay R^3 at the right-hand end of this section is a repeater of the auxiliary relay X^8 at the left-hand end, and similarly, relay R^4 at the left-hand end serves as a repeater for auxiliary relay X^4 at the right-hand end. Both of these repeater relays are normally open. Relay R^3 is provided with a circuit which passes from the secondary of transformer U^5 , through wire 60, contact 61 of relay W^6 , wires 62 and 92, front point of contact 93 of relay X^8 , wire 94, back point of contact 95 of relay X^4 , wire 96, back contact 97 of track relay T^4 , wire 98, winding of relay R^3 , and wires 99, 29 and 70, contact 71 of relay W^6 and wire 55 to the secondary of transformer U^5 . Inasmuch as relay X^8 is closed only when a train moving toward the right enters section 5-6, it will be seen that this is the only condition under which repeater relay R^3 can be closed. Relay R^3 will not close, however, until the train reaches such a point in the section that track relay T^4 opens, and we will assume that this occurs before the middle track relay B' opens.

When relay R^3 closes, it performs two functions: First, its contacts 100 and 101 disconnect track relay T^4 from the rails of section 5-6 and connect the secondary of transformer C^4 with the track rails in the place of the track relay. Second, it opens the normally closed circuit for the primary of transformer 86, which circuit passes from the secondary of transformer U^5 , through wire 60, contact 61 of relay W^6 , wires 62, 63 and 102, back contact 103 of repeater relay R^4 , wire 104, primary of transformer 86, wire 105, back contact 106 of repeater relay R^3 , wires 107, 29 and 70, contact 71 of relay W^6 , and wire 55 to transformer U^5 .

The circuit for repeater relay R^4 is sub-

stantially the same as that for relay R^3 , the sole difference being that the circuit for relay R^4 passes through signal operated pole-changer P^5 instead of a pole-changing relay corresponding to relay W^6 . The control of relays R^2 and R^5 in section 6-7 and the functions of these relays, are the same as the control and functions of the corresponding relays in section 5-6.

10 In section 4-5 the auxiliary relay X' is provided with a repeater relay R' , the circuit for which passes from transformer U^4 , through wires 109 and 108, contact 110 of relay X' , wire 111, back point of contact 112, of track relay T' , wire 113, back point of contact 114 of track relay T^6 , wire 115, winding of relay R' , and wires 116, 55, 56 and 57 to transformer U^4 . When relay R' is closed, it disconnects track relay T^6 from the rails of section 4-5 and connects transformer C^6 with these rails.

The operation of the apparatus thus far described, is as follows:

25 We will first assume that a train moving toward the right passes through the stretch of track shown in the drawing. While such train is still in the portion of track to the left of signal S^8 it will, of course, have placed the latter signal at stop, so that the circuit for line relay A^6 is open at contact 48 on track relay T^6 . Signal S^6 is therefore, in the stop position and relay W^6 is open, because its circuit is broken at contact 78 on signal S^6 . The result of this is that signal S^4 is in the caution position, because relay A^4 is supplied with current of reverse relative polarity. As the train passes signal S' it opens track relay T' , which in turn opens line relay A' , so that signal S' moves to the stop position. The opening of track relay T' also closes auxiliary relay X' and the latter relay subsequently remains closed as long as relay T' is open, because the holding circuit for relay X' includes a back contact 117 of relay T' . Track relay T^6 also opens as soon as the train enters section 4-5, because track transformer C' , the only source of track circuit current for this section is immediately shunted. Repeater relay R' is therefore closed as soon as the train enters the section and so track relay T^6 is disconnected from the rails and transformer C^6 is connected with the rails instead. The connection between transformer C' and the track rails includes a back contact 118 of relay X' , so that as long as the train occupies section 4-5 this transformer is disconnected from the rails in the rear of the train. When the train passes out of section 4-5 the current from transformer C^6 energizes track relay T' over the track circuit, and the consequent closing of this relay opens relay X' , which in turn opens relay R' , whereupon transformer C^6 is disconnected from the rails and track relay T^6 is

re-connected with the right-hand end of section 4-5. The opening of relay X' of section 4-5 again connects transformer C to the left-hand end of the section, so that both track relays T' and T^6 for this section 70 become energized.

When the train enters section 5-6, track relay T^3 is de-energized, the auxiliary relay X^3 closes and while the train is proceeding through the left-hand portion of this section 75 it receives track circuit current from transformer 86. After reaching a point near the middle of the section, however, track relay T^4 at the right-hand end opens, whereupon relay R^3 closes, thereby replacing track relay T^4 with transformer C^4 and also opening the branch primary circuit for transformer 86. Subsequently the middle track relay B' opens and thereby disconnects transformer 87 from the primary of transformer 86, so 80 that the supply of current to the middle of the section is discontinued. The train receives track circuit current, however, from transformer C^4 until it leaves section 5-6. While the train is in the right-hand half of section 5-6 there is no source of track circuit current connected with the rails in the rear of the train, because the branch primary circuit for transformer 86 is open at repeater relay R^3 and the secondary circuit for transformer 87 is open at the contacts of relay B' ; relay B' remains open, of course, because there is no track circuit current to close it. When the train leaves section 5-6, track circuit current from transformer C^4 will first close relay T^3 . This de-energizes X^3 , which opens the circuit for relay R^3 , so that transformer C^4 is disconnected from the rails and track relay T^4 is again connected therewith. It also closes the 85 branch circuit for transformer 86 so that current is again supplied to the middle of the section, closing B' , connecting 86 again direct to source 87. Relay T^4 closes as soon as it is again placed in the track circuit and so the entire track circuit for section 5-6 is restored to normal condition. As soon as the rear of the train passes out of section 4-5, current of reverse relative polarity is supplied to relay A' from the secondary of reversing transformer H^3 , contact 58, wire 163, contact 164 of relay X^3 , wires 165 and 166, thence over the contacts of T^6 and T' to relay A' , so that relay A' is energized in the reverse direction and signal 31 moves to 110 the caution position.

As soon as the train leaves section 5-6, relay T^3 will be closed; the circuit of A' is however not opened thereby, because the branch through contact 164 of X^3 is replaced by the branch from contact 58 through contact 167 of relay T^3 to wire 166. Relay A^3 will now be energized with current of reverse polarity over T^3 , line wire 25, relays T^4 and X^5 and pole-changer P^5 so that 125

signal S^3 will indicate caution. Relay A' will now receive current of normal polarity from transformer U^5 over contact 58 operated by signal S^3 , so that signal S' will indicate proceed.

The operation of the apparatus as the train passes through section 6-7 will be understood from the foregoing without further explanation.

- 10 During the movement of a train toward the left repeater relay R^4 closes as the train approaches the middle of section 5-6 and this relay, of course, removes track relay T^3 from the track circuit and places transformer C^3 therein. As such train enters section 4-5, it opens track relay T^6 , but has no effect on relays R' and X' , and so transformer C' supplies track circuit energy to the train throughout the entire length of 20 the section.

- The apparatus shown in Fig. 1 also includes means for at times supplying what we will term a "local" current to the track rails, which current flows in the same direction in 25 the two track rails or, in other words, flows through these rails in multiple. The purpose of this current will be explained hereinafter. Considering section 5-6, for example, when a train moving toward the right enters this section, the opening of track relay T^3 closes the following circuit: from the secondary of transformer U^6 , through wire 18, pole-changer P^5 , wire 19, wire 20, contact 21 of line relay A^5 , wire 22 and 23, contact 24 of track relay T^4 , wire 25, back point of contact 26 of track relay T^3 , wire 119, back point of contact 120 of repeater relay R^4 , wire 121, primary of a transformer K^3 , wires 122, 28 and 29, pole-changer P^5 and wire 30 to transformer U^6 . The secondary of transformer K^3 then supplies current to the track rails of section 5-6 between a resistance J^2 and a resistance J^1 the circuit being from the middle point of resistance J^2 , wire 126, the secondary of transformer K^3 , wire 123, contact 124 of relay X^3 , wire 125 to resistance J' , then through the track rails 2 and 2^a in multiple to resistance J^2 . Inasmuch as the primary circuit for transformer K^3 includes the pole-changer P^5 which is operated by signal S^5 , it will be seen that the local current thus supplied to the track rails will be of normal or reverse relative polarity, depending on the 55 position of signal S^5 . We will assume that when signal S^5 indicates proceed or caution this current will be of normal relative polarity, and when signal S^5 indicates stop the current will be of reverse relative polarity.

- 60 When the train moving toward the left proceeds far enough into section 5-6 to open track relay T^4 , the repeater relay R^3 closes, and this in turn closes a circuit for the primary of a transformer K^4 , which circuit passes from the secondary of trans-

former U^6 , through wire 18, pole-changer P^5 , wires 19, 34 and 127, front point of contact 128 of relay R^3 , wire 129, primary of transformer K^4 , wires 130 and 29, pole-changer P^5 and wire 30 to the secondary of transformer U^6 . If signal S^5 indicates proceed or caution, the secondary circuit for transformer K^4 is closed to supply local current to the track rails from resistance J^3 to resistance J^4 , this circuit being from the 70 middle point of resistance J^3 through wires 134 and 133, contact 132, wire 131 to the secondary of transformer K^4 , thence over wire 135 to resistance J^4 , and over the track rails in multiple to J^3 . This current will be of 75 normal relative polarity because the primary circuit for transformer K^4 includes pole-changer P^5 and this pole-changer delivers current of normal relative polarity when signal S^5 indicates proceed or caution. If 80 signal S^5 indicates stop, the secondary circuit for transformer K^4 will be from J^5 to J^4 instead of from J^3 to J^4 , this circuit being from the middle point of J^5 over wire 136, wire 131, the secondary of K^4 , wire 135 to 85 resistance J^4 , the rails 2 and 2^a in multiple, to resistance J^5 . This current will be of reverse relative polarity because pole-changer P^5 is reversed when contact 132 is reversed.

It will be seen from the foregoing that 90 when a train moving toward the right passes through section 5-6 it will receive local current of normal relative polarity throughout the entire section if signal S^5 indicates proceed or caution, or local current of reverse 95 relative polarity from resistance J' to resistance J^5 if signal S^5 indicates stop.

It should here be pointed out that the apparatus shown in the present application is intended for co-operation with train-carried 100 mechanism so constructed that when the mechanism receives track circuit current as well as local current of normal relative polarity the train may proceed at full speed; when the train-carried mechanism receives track circuit current and local current of reverse relative polarity, the train may proceed at an intermediate speed; and when the train receives track circuit current alone it 105 may proceed at a low speed. In all three instances the brakes will be applied if the train exceeds the speed permitted by the characteristics of the currents received from the trackway.

When a train moving toward the left 110 passes through section 5-6 local current of normal relative polarity will be supplied to the rails of this section throughout the length of the section if signal S^6 indicates proceed or caution, and local current of reverse 115 polarity will be supplied from resistance J^3 to resistance J^6 if signal S^6 indicates stop. The apparatus and circuits for supplying current during the passage of a train moving toward the left are the same as 120

that just described for the passage of a train moving toward the right with one exception. When a train is in section 5-6 approaching S^8 its local circuit is energized from transformer K^3 whose primary is controlled by the pole-changer contacts of relay W^6 . If now, the train passed signal S^4 at clear, and an opposing train should cause signal S^8 to go to stop, the main circuit for relay W^6 would be opened thereby; the de-energization of W^6 , and the consequent reversal of the local circuit under the train is prevented, however, because of a branch circuit for relay W^6 . This branch circuit is from transformer U^5 through wires 9, 83, stick contact 84 of relay W^6 , wires 85, 77, contact 78, wire 79, relay W^6 , wires 80 and 16 to transformer U^5 . The local circuit is therefore, not reversed until signal S^8 goes to stop, in which case this holding circuit for relay W^6 is opened at contact 78. Section 6-7 and the portion of the section shown to the right of point 7 in Fig. 1^B are equipped with apparatus similar to that just described for section 5-6 for supplying local current to the track rails.

The apparatus shown for supplying local current to the rails of section 4-5 is as follows:

Assuming that a train moving toward the right enters this section, the closing of relay X' and repeater R' will close a circuit from resistances J^3 to J' for section 4-5, this circuit being from the middle point of resistance J^3 , wires 140 and 139, contact 138, wire 137, the secondary of transformer K^3 , wire 148, contact 147 of relay R' , wire 146, contact 145 of relay T^6 , wire 144, contact 143 of relay X' wires 142 and 141 to resistance J' , thence over the track rails of section 4-5 in multiple to resistance J^3 . In tracing this circuit we have assumed that signal S^3 indicates proceed or caution. This being so, it will be noted that the local current is supplied to section 4-5 throughout the entire length of this section and for reasons which we will explain hereinafter this current is of normal relative polarity owing to the position of contact 58 which controls the polarity of the primary circuit of transformer K^3 . If signal S^3 is at stop, however, then the circuit for the secondary of transformer K^3 will be from J^3 over wire 149 to contact 138, instead of from J^3 to 138. Under this condition local current is supplied only from resistance J^3 at an intermediate point in the block, to J' at the entrance end of the block, and owing to the fact that contact 58 is reversed, this current will be of reverse relative polarity.

When a train moving toward the left enters section 4-5, the opening of track relay T^6 will close at contact 145 the secondary circuit for transformer K^3 , thereby supplying local current of normal relative polarity

throughout the length of the section if signal S^3 indicates proceed or caution, and local current of reverse relative polarity from resistance J^4 to resistance J^3 of section 4-5 if signal S^3 indicates stop. The secondary circuit for transformer K^3 is similar to the circuit traced hereinbefore for transformer K^3 and will be apparent from the drawing without further explanation.

The polarity of the current supplied to the local circuit for section 4-5 during a train movement to the right is controlled by contact 58 operated by signal S^3 and by reversing transformer H^3 , the operation of these parts being as follows: When signal S^3 is in the proceed or caution position the right-hand terminal of the primary of transformer K^3 is connected with the secondary of transformer U^5 by means of contact 58, and wire 9, the left-hand terminal of the primary of K^3 being connected with the secondary of U^5 by wire 16; current of normal relative polarity is then supplied to the local circuit for section 4-5. When signal S^3 indicates stop, however, the contact 58 breaks the direct connection between transformers K^3 and U^5 , and contact 58 then connects the primary of K^3 with the secondary of transformer H^3 ; the primary of transformer H^3 is constantly connected with the secondary of transformer U^5 . The right-hand terminal of the secondary of U^5 is connected with the right-hand terminal of the primary of H^3 , by wire 9 and the right-hand terminal of the secondary of H^3 is connected with the left-hand terminal of the primary of K^3 , so that current of reverse relative polarity is then supplied to the local circuit for section 4-5.

The polarity of the current supplied to the local circuit for section 4-5 while a train is moving toward the left is similarly controlled by a contact 45 operated by signal S^3 and by transformer H^3 .

Referring now to Fig. 2, we have here shown a modification of the apparatus associated with section 5-6, which apparatus is the same as that shown in Fig. 1^B, except as to the means for disconnecting the source of track circuit current from the middle of the section, and except as to certain details concerning the circuits for the local current.

In Fig. 2 the track circuit current is supplied to the rails at the middle of the section 5-6 by a transformer 87, the primary of which is constantly connected with the transmission line L and the secondary of which is connected with the rails through back contacts of relay B^2 . Relay B^2 is normally open but is closed whenever a train passes through the section in either direction. Assuming for example, that a train is moving toward the right, when this train reaches such point that it opens track relay T^4 , relay B^2 and

repeater relay R^3 becomes closed by virtue of a circuit which passes from the secondary of transformer U^5 , through wire 60, contact 61 of relay W^6 , wires 62 and 92, front point of contact 93 of relay X^3 , wire 94, winding of relay B^2 , wire 94^a, back point of contact 95 of relay X^4 , wire 96, back contact 97 of track relay T^4 , wire 98, winding of repeater relay R^3 , wires 99, 29 and 70, contact 71 of relay W^6 , and wire 55 to the secondary of transformer U^6 . When relay B^2 closes it of course disconnects transformer 87 from the rails and the closing of track relay T^4 connects transformer C^4 with the rails at the 15 end of the section, so that the train is supplied with track circuit energy from the right-hand end of the section as long as the train occupies the section but no source of track circuit is supplied in the rear of the 20 train. When the train passes out of section 5-6, track relay T^3 closes, due to current from transformer C^4 , and the closing of track relay T^3 opens the holding circuit for auxiliary relay X^3 , so that the latter relay 25 also opens. The opening of X^3 opens the circuit for relays B^2 and R^3 , so that transformer 87 is again connected with the rails at the middle of the section and track relay T^4 is again connected with the rails at the 30 right-hand end of the section. The two track relays then become energized from transformer 87 and so the parts of the track circuit are restored to their original conditions.

When a train moving toward the left passes through section 5-6, relays B^2 and R^4 are closed by virtue of a circuit which is similar to the circuit previously traced for B^2 and R^3 , and, in fact, the operation is 40 symmetrical in every respect to the operation of the passage of a train moving toward the right.

Local current is supplied to the rails of section 5-6 from resistance J^2 to resistance J' by a transformer K^3 , and from resistance J^3 to resistance J^4 by a transformer K^4 . The secondary circuit for transformer K^3 is from resistance J^2 , wire 151, the secondary of K^3 , through wire 150, resistance J' , track rails 2 and 2^a, to resistance J^2 . When a train moving toward the right passes through section 5-6, the primary circuit for transformer K^3 is from the secondary of transformer U^6 , through wire 18, pole-changer P^6 , wires 19 and 20, contact 21 of relay A^5 , wires 22 and 23, contact 24 of track relay T^4 , wire 25, back point of contact 26 of track relay T^3 , wire 119, back point of contact 120 of repeater relay R^4 , wire 121, primary of transformer K^3 , wires 122, 28 and 29, pole-changer P^6 , and wire 30 to the secondary of the transformer U^6 . This circuit is closed when track relay T^4 is closed and track relay T^3 is open, and, consequently, transformer K^3 supplies current to

the rails only until the train reaches such point that it opens track relay T^4 . This current will be of normal relative polarity when signal S^5 indicates proceed or caution, and of reverse relative polarity when such signal indicates stop.

The secondary circuit for transformer K^4 passes from resistance J^3 , wire 155, secondary of K^4 , wire 156, resistance J^4 , track rails 2 and 2^a to resistance J^3 . When a train moving toward the right reaches such point that track relay T^4 opens, the repeater relay R^3 becomes closed by virtue of a circuit traced hereinbefore, and if signal S^5 indicates proceed of caution, local current 50 of normal relative polarity is then supplied to the primary of transformer K^4 through a circuit which passes from the secondary of transformer U^6 , through wire 18, pole-changer P^6 , wire 154, contact 153, wire 152, front point of contact 128 of repeater relay R^3 , wire 129, primary of transformer K^4 , wire 29, pole-changer P^6 , and wire 30 to the secondary of transformer U^6 . If signal S^5 indicates stop, however, the primary circuit for transformer K^4 is opened at contact 153 operated by this signal, and so there is no local current supplied to the rails between resistances J^2 and J^3 in section 5-6.

The operation of the apparatus during the passage of a train moving toward the left will be apparent from the foregoing without further explanation.

Although we have herein shown and described only two forms of apparatus embodying our invention, it is understood that various changes and modifications may be made therein within the scope of the appended claims without departing from the spirit and scope of our invention.

Having thus described our invention, what we claim is:

1. In combination, a section of railway track, a track circuit for said section including a source of alternating current connected with the rails adjacent the middle of the section and two track relays connected with the rails adjacent the two ends of the section, and means controlled by said relays when affected by a train in the section for disconnecting from the rails the track relay in advance of the train and connecting a source of alternating current with the rails in its place.

2. In combination, a section of railway track, a track circuit for said section including a source of alternating current connected with the rails adjacent the middle of the section and two track relays connected with the rails adjacent the two ends of the section, and means controlled by said relays when affected by a train in the section for disconnecting said source of current and the track relay in advance of the

train from the rails of the section and connecting an auxiliary source of current with the rails in place of the track relay.

3. In combination, a section of railway track, a track circuit for said section including a source of alternating current connected with the rails adjacent the middle of the section and two track relays connected with the rails adjacent the two ends 5 of the section, and means controlled by said relays when affected by a train in the section for disconnecting said source of current from the rails and keeping it disconnected until the train leaves the section.
- 15 4. In combination, a section of railway track, a track circuit for said section including a source of alternating current connected with the rails adjacent the middle of the section and two track relays connected with 20 the rails adjacent the two ends of the section, a normally open auxiliary relay at each end of the section, means controlled by each track relay when opened by a train entering the section at the corresponding end for closing the auxiliary relay at that end and 25 keeping it closed until the train leaves the section, two normally open repeater relays one at each end of the section and each operating when closed to disconnect the associated track relay from the track rails and connect a source of alternating current with the rails in its place, and means for closing each repeater relay when the auxiliary relay at the other end of the section and both track 30 relays are open.
5. In combination, a section of railway track, a track circuit for said section including a source of alternating current connected with the rails adjacent the middle of the section and two track relays connected with the rails adjacent the two ends of the section, a normally open auxiliary relay at each end of the section, means controlled by each track relay when opened by a train entering the section at the corresponding end for closing the auxiliary relay at that end and 45 keeping it closed until the train leaves the section, two normally open repeater relays one at each end of the section and each operated when closed to disconnect said source of current and the track relay associated with the repeater relay from the rails and connect a source of alternating current with the rails in place of such track relay, and means for closing each repeater relay when the auxiliary relay at the other end of the section and both track relays are open.
- 50 6. In combination, a section of railway track, two track relays connected with the rails at the ends of said section and a third track relay connected with the rails adjacent the middle of the section, a main source of current connected with the rails adjacent the middle of the section and controlled by a front contact of such relay, an auxiliary 55 source of current also connected with the rails adjacent the middle of the section, and means controlled by said end track relays when affected by a train passing through said section for disconnecting said auxiliary source from the rails as the train approaches the middle of the section and for keeping said auxiliary source disconnected thereafter until the train leaves the section.
7. In combination, a section of railway track, two track relays connected with the rails at the ends of said section and a third track relay connected with the rails adjacent the middle of the section, a main source of current connected with the rails adjacent the middle of the section and controlled by a front contact of such relay, an auxiliary source of current also connected with the rails adjacent the middle of the section, and means controlled by said end track relays when affected by a train passing through said section for disconnecting said auxiliary source from the rails as the train approaches the middle of the section and for keeping said auxiliary source disconnected thereafter until the train leaves the section, and means also controlled by said track relays when affected by a train passing through the section for disconnecting the end track relay in advance of the train from the rails and connecting a source of alternating current with the rails in its place.
8. In a railway traffic controlling system of the type comprising a stretch of track divided into sections, a source of alternating current connected with the rails of each section adjacent the middle of the section, two track relays normally connected with the rails of each section adjacent the two ends of the section respectively, two signals for each section for governing traffic in opposite directions through the section, a line relay for each signal, means for controlling each line relay by both track relays for the associated section and also by the line relay for the signal next in advance governing traffic in the same direction, a normally open auxiliary relay for each signal arranged when energized to eliminate the associated line relay from the controlling means for the line relay next in the rear, means for closing each auxiliary relay when a train passes the associated signal moving in the direction in which the signal governs traffic and for subsequently keeping it closed until the train leaves the section governed by such signal; the combination with the foregoing instrumentalities of two normally open repeater relays one at each end of one of said sections and each operating when closed to disconnect the adjacent track relay from the rails of said section and connect a source of alternating current with such rails, and means for closing each repeater relay when the adjacent auxiliary relay and the adjacent track 100

relay are opened and the auxiliary relay at the opposite end of the section is closed.

9. In combination, a section of railway track over which traffic moves in both directions, means operating when a train enters said section from either end to supply local current to the rails from the end at which the train enters to an intermediate point in the section, and means operating before the train reaches such intermediate point to supply local current to the rails from a point in the rear of said points to the end at which the train will leave the section.

10. In combination, a section of railway track over which traffic moves in both directions, means operating when a train enters said section from either end to supply local current to the rails from the end at which the train enters to an intermediate point in the section, said current being of one relative polarity or the other according to traffic conditions beyond the section in the direction in which the train is moving; and means operating before the train reaches said intermediate point to supply local current of normal relative polarity to the rails from a second intermediate point in the rear of the first to the end at which the train will leave the section, or of reverse relative polarity from said second intermediate point to a third intermediate point in advance of the second, according to traffic conditions beyond the section in the direction in which the train is moving.

11. In a railway traffic controlling system of the type comprising a stretch of track divided into sections, a source of alternating current connected with the rails of each section adjacent the middle of the section, two track relays normally connected with the rails of each section adjacent the two ends of the section respectively, two signals for each section for governing traffic in opposite directions through the section, a line relay for each signal, means for controlling each line relay by both track relays for the associated section and also by the line relay for the signal next in advance governing traffic in the same direction, a normally open auxiliary relay for each signal arranged when energized to eliminate the associated line relay from the controlling means for the line relay next in the rear, means for closing each auxiliary relay when a train passes the associated signal moving in the direction in which the signal governs traffic and for subsequently keeping it closed until the train leaves the section governed

by such signal; the combination with the foregoing instrumentalities of two normally open repeater relays one at each end of one of said sections, means for closing each repeater relay when the auxiliary relay at the opposite end of said section is closed and the section is occupied by a train approaching such repeater relay, means controlled by each auxiliary relay when closed for supplying local current to the track rails from the adjacent end to an intermediate point in the section of normal or reverse relative polarity according to traffic conditions in advance of the section, and means controlled by each repeater relay when closed for supplying local current of normal relative polarity to the rails from a second intermediate point in the rear of the first to the end adjacent the repeater relay or of reverse relative polarity from said second intermediate point to a third intermediate point in advance thereof according to traffic conditions in advance of the section.

12. In combination, a section of railway track, a track circuit for said section including a source of alternating current connected with the rails adjacent the middle of the section and two track relays connected with the rails adjacent the two ends of the section, and means controlled by said relays when affected by a train in the section for disconnecting a normally open relay arranged when closed to disconnect said source of current from the rails, and means controlled by said track relays when affected by a train passing through the section for closing said normally open relay before the rear of the train passes said source and keeping it closed until the train leaves the section.

13. In combination, a section of railway track over which traffic moves in both directions, means operating when a train enters said section from either end to supply local current to the rails from the end at which the train enters to an intermediate point in the section, and means operating before the train reaches said intermediate point to supply local current to the rails from a point in the rear of said point to the end of the section under clear traffic conditions in advance but not under unsafe traffic conditions in advance.

In testimony whereof we affix our signatures.
